UNITED STATES PATENT OFFICE.

JOSEPH R. RICHER, OF CHICAGO, ILLINOIS.

ROTARY PUMP AND THE LIKE.

Application filed August 11, 1921. Serial No. 491,326.

To all whom it may concern:

Be it known that I, JOSEPH R. RICHER, a citizen of the United States, residing at Chicago, in the county of Cook and State of Illinois, have invented certain new and useful Improvements in Rotary Pumps and the like, of which the following is a specification.

The invention relates to rotary devices such, for example, as rotary pumps, motors, etc., embodying a cylinder element and a rotor element, the latter being mounted eccentrically with respect to the former and equipped with pressure devices such as slidable vanes adapted operatively to engage the inner peripheral wall of the cylinder element.

The principal object of the invention is to provide a device of the character stated which is highly efficient in operation by reason of the elimination of a substantial amount of the friction which accompanies the operation of this class of devices as ordinarily constructed.

More specifically stated, the object of the invention is to provide a device of this character in which the two main coacting operating elements are both rotatably mounted so that the driven element, through frictional contact with the other element, causes it to rotate and thus substantially reduces the amount of friction therebetween without in any way affecting the operation of the device.

A further and general object of the invention is to provide a device of this character which is in the form of a pump of an efficient and practical character.

The objects of the invention thus generally stated, together with other and ancillary advantages, may be attained by the construction and arrangement illustrated in the accompanying drawings forming part hereof in which I have illustrated a pump which is particularly adapted for use as a blower or vacuum pump. It will be understood, however, that the invention in its broad aspect is not limited to a pump, wherein the vane or other pressure device constitutes an impeller for driving a fluid, it being obvious that it is applicable equally advantageously to other devices of this general class, such, for example, as rotary mo-

tors, wherein the pressure device constitutes a piston actuated by the fluid. Moreover, in the interpretation of the appended claims, the invention is not to be understood as limited to the precise form, construction or arrangement of parts herein illustrated and described except as may be necessitated by the state of the prior art.

In the drawings, Figure 1 is a vertical central sectional view through a pump embodying my invention. Fig. 2 is an end elevational view of the same. Fig. 3 is a horizontal sectional view taken substantially in the plane of line 3—3 of Fig. 1. Fig. 4 is a fragmentary detail sectional view illustrating a portion of the means for guiding one of the operating elements in its rotation. Fig. 5 is a detached elevational view of the rotor element and its pressure device.

The device comprises primarily a cylinder element 7, and a rotor element 8 mounted eccentrically with respect to the cylinder element. A pressure device 9, in the form of one or more vanes, is adapted to coact with the cylinder and rotor element in the operation of the device, in the well-known manner.

Herein the cylinder element 7 is rotatably mounted within an outer housing or casing 10 comprising a main or central portion 10^a and end or side plates 10^b and 10^c. The parts of the casing are secured together by means of bolts 11. At substantially equidistantly spaced points within the casing, a plurality of rollers 12, 12^a and 12^b engage with the outer periphery of the element 7.

Herein the rotor element is mounted so that its periphery engages the inner periphery of the cylinder at approximately the uppermost point in the circumference of the cylinder element, and the rollers 12 and 12^a are located upon opposite sides of the cylinder element and the roller 12^b at the top side of the cylinder element. These rollers are mounted within recesses 13 formed in radial enlargements 14 of the casing. Preferably the rollers 12 and 12^a are mounted upon fixed pivots 15 and the roller 12^b is mounted upon a movable pivot 16 and adapted to exert a yielding pressure upon the outer periphery of the cylinder element whereby to hold it in operative contact with the rotor.

Referring to Fig. 4, the mounting for the shaft or pivot pin 16 for the roller 12^b comprises a pair of studs 17 projecting radially inwardly into the uppermost recesses 13 and having reduced inner end portions 17^a entered through apertures near the opposite end of the pin 16. A pair of coiled expansion springs 18 encircle the studs and bear between the casing at the inner end of said recess on the one hand and the pin on the other hand. The roller 12^b thus exerts a yielding pressure upon the outer periphery of the cylinder element 7 and serves to hold said element in operative contact with the periphery of the rotor 8.

The rotor element 8 is journaled in the end plates 10^b and 10^c as shown in Fig. 3. To this end the plate 10^b is provided with a lateral extension 19 providing a bearing 20 for receiving a journal 21 on one end of the rotor, and the plate 10^c is provided with a lateral extension 22 providing a bearing for a shaft 23 rigid with the opposite end of the rotor and adapted for connection with a source of motive power. Preferably the rotor is divided transversely substantially centrally thereof to provide two interfitting sections 8^a and 8^b. These sections are maintained in relative rotative alinement by means of a pair of dowel pins 24, and are yieldingly held apart by means of a pair of coiled expansion springs 25. Preferably the outer end portions of each of the sections 8^a and 8^b are entered into sockets 26 formed in the inner sides of the end plates 10^b and 10^c of the casing. The rotor proper is thus journaled in the side walls of the casing, and by reason of the peculiar construction and mounting thereof serves effectively to prevent the leakage of pressure fluid between it and the sides of the casing.

Herein I employ two pressure members 9 which are in the form of vanes slidably mounted within the rotor 8 and yieldingly held in sliding engagement with the inner periphery of the cylinder 7. Referring to Fig. 3, these vanes are preferably formed by means of a pair of interfitting plate members 27 having a spring 28 interposed therebetween so as to yieldably force the plates apart. The rotor sections 8^a and 8^b are provided with transverse slots or grooves 29 and 30 in their inner faces, adapted to receive the opposite edges of said plates 27. The plates 27 are notched at their inner edges into stepped formation so as to coact in interfitting relation while providing between them a recess for the reception of the spring 28, and it will be observed that each plate has a portion of substantial length engaging in one of the grooves so as to resist effectively torsional strains.

The casing 10 has an inlet and an outlet arranged respectively on opposite sides of the rotor. Herein 31 designates the inlet

and 32 the outlet. These outlets are in the form of elongated slots (Fig. 1) arranged between the cylinder element 7 and the rotor 8, upon opposite sides of the rotor and preferably near its point of contact with the cylinder. Assuming then, the operation of the rotor in the direction of the arrow in Fig. 1, in the movement of the pressure member 9 adjacent the inlet 31 away from the inlet, it causes an induction of fluid into the interior of the cylinder, forcing before it to the outlet 32 the fluid previously drawn into the cylinder through said inlet. Herein both the inlet and the outlet are formed in the plate 10^b of the casing and lateral extensions 33 are provided for the reception of inlet and outlet pipes when desired. Herein I have illustrated such an outlet pipe 34.

In the operation of the device, it will be apparent that the cylinder element 7, by reason of its frictional contact with the rotor 8, rotates in the same direction as the rotor but of course at a somewhat slower speed. The friction thus produced between the two parts, however, is relatively slight, and the rotation of the cylinder has no effect upon the ability of the device to accomplish its intended function. Heretofore devices of this character have been wholly impractical in cases where high speed is required. With the present construction, however, the substantial elimination of friction and hence of excessive heat, renders the device well adapted for high speed purposes, as for example, as vacuum pumps, blowers, motors, etc. wherein an extremely high speed is required. Moreover, even when high speed is not required, my invention is advantageous since the life of the device is materially prolonged by reason of the reduction of wear between the operating parts.

I claim as my invention:

1. A device of the class described comprising, in combination, a stationary casing, a cylinder rotatably mounted in said casing, a rotor journaled in said casing eccentrically of said cylinder, and a pressure member carried by the rotor and adapted operatively to engage the inner periphery of said cylinder, said cylinder being freely rotatable with respect to said rotor and adapted to yield relative thereto.

2. A device of the class described comprising, in combination, a stationary casing, a cylinder rotatably mounted in said casing, a rotor journaled in said casing eccentrically of said cylinder, a pressure member carried by the rotor and adapted operatively to engage the inner periphery of said cylinder, said cylinder being freely rotatable with respect to said rotor, and means operable to exert a yielding pressure against said cylinder whereby to hold it in operative contact with the rotor.

3. In a device of the class described, the combination of a casing, a cylinder within said casing, and a rotor mounted eccentrically within said cylinder, said cylinder being yieldable relative to said rotor.
4. In a device of the class described, comprising, in combination, a casing, a cylinder within the casing, a rotor mounted eccentrically within the cylinder, means rotatably guiding the cylinder for rotation independently of while supported by the rotor, said means being yieldable for relative displacement of the rotor and cylinder, and a pressure member carried by one of said rotatably elements and operatively engaging with the other element.
5. In a device of the class described, in combination, a cylinder element, a rotor element mounted eccentrically of said cylinder element, a pressure member carried by one of said elements and operatively engaging the other, and means rotatably guiding said cylinder for rotation independently of while supported by said rotor element said means being yieldable for relative displacement of the rotor and the cylinder.
6. In a device of the class described, the combination of a cylinder element, a rotor element mounted eccentrically of said cylinder element, a pressure member carried by one of said elements and operatively engaging the other, and means for guiding said cylinder for rotation independently of while supported by said rotor element, said means comprising a pair of rollers operatively engaging the periphery of said cylinder upon substantially diametrically opposite sides thereof, and a third roller therebetween yieldingly forcing said cylinder against said rotor.
7. In a device of the class described, the combination of a cylinder element, a rotor element mounted eccentrically of said cylinder element, a pressure member carried by one of said elements and operatively engaging the other, and means rotatably guiding said cylinder for rotation independently of said rotor element, said means comprising a plurality of rollers operatively engaging the periphery of said cylinder, one of said rollers being adapted to exert a yielding pressure upon the cylinder.
8. In a device of the class described, the combination of a rotor, and a cylinder within which said rotor is eccentrically disposed, said cylinder having an operative engagement with said rotor, the rotor being mounted upon a fixed axis and the cylinder upon a movable axis.
9. In a device of the class described, the combination of a rotor, a cylinder within which said rotor is eccentrically disposed, said cylinder being mounted upon a movable axis and having an operative engagement with said rotor so as to be supported thereby,
- and means adapted to maintain the cylinder against lateral movement with respect to the axis of said rotor.
10. In a device of the class described, the combination of a casing, a cylinder mounted upon a movable axis and adapted to rotate freely within said casing, a rotor mounted eccentrically of said cylinder on an axis fixed with respect to the casing and adapted to support the cylinder, and a pressure member carried by the rotor and operatively engaging the inner periphery of the cylinder, said casing having an inlet and an outlet communicating with the interior of the cylinder upon opposite sides of said rotor.
11. In a device of the class described, the combination of a casing, a cylinder, a rotor mounted upon a fixed axis in the casing and eccentrically of the cylinder, and means tending to hold said cylinder in operative contact with said rotor comprising a roller, a shaft carrying said roller, and spring means bearing between said shaft and the casing tending to move the roller inwardly.
12. In a device of the class described, the combination of a casing, a cylinder, a rotor mounted upon a fixed axis in the casing and eccentrically of the cylinder, and means tending to hold said cylinder in operative contact with said rotor comprising a roller, a pair of studs carried by the casing and slidably engaging said shaft at their inner ends, and springs between said casing and said shaft encircling said studs.
13. In a device of the class described, the combination of a casing, a cylinder mounted in said casing with its axis movable in a transverse plane, and a rotor mounted upon a fixed axis within the cylinder concentrically thereof and adapted operatively to engage with the cylinder at a point approximately in said plane.
14. The combination of a casing, a cylinder, means for supporting the cylinder in the casing with its axis movable in a transverse plane, and a rotor mounted upon a fixed axis concentrically of the cylinder and adapted operatively to engage with the cylinder at a point approximately in said plane, said means being adapted to maintain the axis of said cylinder substantially in said plane.
15. The combination of a casing, a cylinder, means for supporting the cylinder in the casing with its axis movable in a transverse plane, and a rotor mounted upon a fixed axis concentrically of the cylinder and adapted operatively to engage with the cylinder at a point approximately in said plane, said means being adapted to maintain the axis of said cylinder substantially in said plane while permitting the cylinder to rotate relative to the casing.
16. The combination of a cylinder mounted for movement with its axis traveling in

a plane extending transversely of the cylinder substantially diametrically thereof, and a rotor mounted upon a fixed axis eccentrically of the cylinder with its periphery 5 operatively engaging the inner periphery of the cylinder at a point approximately in said plane.

17. The combination of a cylinder mounted for movement with its axis traveling in 10 a plane extending transversely of the cylinder substantially diametrically thereof, a rotor mounted upon a fixed axis eccentrically of the cylinder, and means tending at all 15 times to move said cylinder in said plane against the rotor.

18. The combination of a casing having a cylindrical chamber therein, a cylinder adapted to be inserted into said chamber and having an internal diameter less than the 20 external diameter of the chamber, a rotor mounted upon a fixed axis eccentrically of said chamber, and means tending to move said cylinder in a plane extending diametrically of the chamber into contact with said 25 rotor.

19. The combination of a casing having a cylindrical chamber therein, a cylinder

adapted to be inserted into said chamber and having an internal diameter less than the external diameter of the chamber, a rotor 30 mounted upon a fixed axis and eccentrically of said chamber, and means tending to move said cylinder in a plane extending diametrically of the chamber into contact with said rotor, said means serving to divide the chamber into inlet and outlet sections communicating with inlet and outlet ports respectively and said rotor having a pressure member slidably engaging the inner peripheral wall of the cylinder. 35

20. The combination of a casing providing a chamber having an inlet and an outlet, a rotor mounted in said chamber, a cylinder also mounted in the chamber and having an internal diameter substantially less than the 40 rotor, and means for effecting relative bodily movement in a fixed path between the rotor and the cylinder whereby to exert at all times a yielding engagement between the cylinder and rotor at a point in said path. 45

In testimony whereof, I have hereunto set my hand.

JOSEPH R. RICHER.
